[57] CLAIM

The ornamental design for an automobile parking pad, as shown and described.

DESCRIPTION

FIG. 1 is a perspective view of the automobile parking pad of the present invention, showing an automobile parked thereon to illustrate the environment of the invention;

FIG. 2 is a fragmentary top plan view of the automobile parking pad of FIG. 1, it being understood that the rib and nipple pattern repeats uniformly across the parking pad;
 FIG. 3 is a side elevational view of the automobile parking pad of FIG. 2, the opposite side elevational view being a mirror image thereof;

FIG. 4 is a fragmentary end view of the automobile parking pad of FIG. 2, the opposite end being a mirror image thereof;
 FIG. 5 is a fragmentary side elevational view of the right-most portion of FIG. 3; and,

FIG. 6 is a fragmentary end view of the left-hand side of FIG. 4.

The broken lines defining an automobile in FIG. 1 are for illustrative purposes only and form no part of the claimed design.

The bottom view of the automobile parking pad is plain and unornamented and, thus, is not illustrated in the accompanying drawings.
